UNITED STATES PATENT OFFICE.

CHARLES S. LINCOLN, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

PORTABLE CRUSHER.

1,257,619.

Specification of Letters Patent. Patented Feb. 26, 1918.

Application filed November 21, 1914. Serial No. 873,666.

To all whom it may concern:

Be it known that I, CHARLES S. LINCOLN, a citizen of the United States, residing at Wauwatosa, in the county of Milwaukee and 5 State of Wisconsin, have invented a certain new and useful Improvement in Portable Crushers, of which the following is a specification.

This invention relates to improvements in 10 the construction of portable crushers and especially to means for maintaining the height of the inlet openings of such crushers at a minimum without interfering with the conveyance of the crusher.

15 An object of the invention is to provide a portable crusher which is simple in construction, efficient in operation, readily accessible for operation, and which may be readily conveyed from one locality to another. One of the more specific objects of 20 the invention is to provide a portable crusher outfit in which the height of the feed openings is reduced to a minimum. Another object is to provide a portable crusher in which 25 the material to be crushed may be fed to the crushers from the ground by hand, and without the use of intermediate elevating operations or devices. Still another object is to provide means for permitting elevation 30 or removal of portions of the device which normally project in proximity to the tread of the vehicle, away from said tread during conveyance of the vehicle, thereby preventing possible injury of these portions and 35 permitting free conveyance of the crusher from one locality to another.

A clear conception of an embodiment of 40 the invention may be had by referring to the drawings accompanying and forming a part of this specification in which like reference characters designate the same parts in the several views.

Figure 1 is a side elevation of a portable 45 crusher outfit embodying the features of the present invention and showing the position of the working parts during normal operation of the crushers.

Fig. 2 is a fragmentary side elevation of 50 a portable crusher outfit embodying the features of the present invention and showing the position of the working parts with the vehicle in condition for conveyance to another locality.

The portable crusher outfit comprises es- 55 sentially a steel framed truck 5 upon which

are mounted a jaw crusher 1, a bucket elevator 2, a rotary impact pulverizer 3, and a helical screw conveyer 4. The jaw crusher 1 has its inlet or feed opening freely accessible and located as near to the ground 60 line 9 as possible, thereby permitting direct manual insertion of the raw material without necessitating the use of intermediate elevating operations or devices. The discharge from the jaw crusher 1 is adapted to be fed 65 by means of suitable devices not forming a part of this invention and therefore not shown, directly into the buckets 17 of the elevators 2, being properly guided into these buckets by means of the apron 6. 70

The bucket elevator 2 comprises a series of buckets 17 secured to the conveyer belt or chain 21, which chain is advanced during normal operation by means of a suitable sprocket drum 15 mounted upon the shaft 75 16. The upper end of the elevator 2 is supported upon a suitable sprocket drum mounted upon the shaft 19, this shaft 19 being supported in adjustable bearings 18 mounted in the uprights 20. The adjustability 80 of the bearings 18 provides means for properly tensioning the belt or chain 21.

The shaft 16 is mounted in the lower ends of a pair of manually movable levers 12, the mid portions of which are pivotally mounted 85 upon the frame of the truck 5 by means of a pivot shaft 13. Each lever 12 is provided with a segmental slot 14 within which a locking cap-screw which is secured to the frame of the truck, coacts. One end of the 90 shaft 16 is provided with a suitable driving pulley 22 which is connected by means of a belt 11 to a pulley on the jaw crusher actuating shaft 10. The jaw crusher actuating 95 shaft 10 is rotatable during normal operation, by means of a suitable motor and belt-ing, not shown.

The buckets 17 of the elevator 2 are adapt-ed to deliver their contents into a telescopic, pivoted spout 7, which in turn delivers to 100 the feed hopper 8 of the rotary impact pul- 105 verizer 3. The discharge from the rotary impact pul- 105 verizer 3 is fed into the lower end of the helical screw conveyer 4, which is adapted to elevate the material and to de- 105 posit the same into a suitable receptacle or wagon.

With the device in normal operating con- 110 dition, the lever 12 is in a vertical posi- 110 tion as shown in Fig. 1, thereby placing the

actuating sprocket drum 15, the pulley 22 and the adjacent buckets 17 of the elevator 2, in close proximity to the ground line 9 forming the tread of the vehicle or truck 5. This location of the drum 15 and pulley 22 as low as possible, permits extreme lowering of the jaw crusher 1 and its discharging devices, so that the mouth of the jaw crusher is readily accessible for feeding from the ground line 9.

In order, however, that the drum 15, pulley 22 and adjacent buckets 17 do not form obstructions during conveyance of the portable outfit, means must be provided for permitting elevation of the downwardly projecting portions during conveyance of the truck 5. This is accomplished by means of the lever 12, which lever after removal of the belt 11 and release of the locking cap-screw within the slot 14, may be swung through an arc of ninety degrees in an anti-clockwise direction, as viewed in Fig. 1, about the pivot 13 as a center, when it assumes the horizontal position shown in Fig. 2. When the lever 12 is in the position shown in Fig. 2, the cap-screw may again be tightened and the drum 15, pulley 22, and the adjacent buckets 17, remain elevated to a sufficient height to give the desired amount of clearance between the working parts and the ground line 9 to permit unobstructed conveyance of the truck 5.

If so desired, the spout 7 may be made to swing sidewise, thereby permitting shunting of the partially reduced material delivered by the jaw crusher 1. To permit such operation, an increase in length of the bucket elevator 2 is necessary since it is preferable in shunting the jaw crusher discharge, to permit delivery of the shunted material into a wagon or other receptacle standing alongside of the portable crusher outfit. The outfit disclosed in the drawing is arranged to permit shunting and may be greatly reduced in overall height if this feature is to be eliminated. It should be noted that the portable outfit herein disclosed is especially applicable for the reduction of limestone and similar materials

for agricultural purposes and that the elimination of preliminary handling of the material fed to the jaw crusher 1 in such equipments is of vast importance.

It should be understood that it is not desired to be limited to the exact details of construction shown and described, for obvious modifications will occur to a person skilled in the art.

It is claimed and desired to secure by Letters Patent:—

1. In combination, a vehicle, material-supplying and receiving devices mounted upon and spaced apart longitudinally of said vehicle, a bucket elevator between said devices, said elevator comprising an upper sprocket, a lower sprocket mounted on a pivot arm and located when in operative position in proximity to the ground surface, and an endless carrier having substantially vertical stretches connecting said sprockets, means for moving said lower sprocket away from said material-supplying means to swing it up away from the ground for transportation, and means for driving said elevator through said lower sprocket.

2. In combination, a vehicle, material-supplying and receiving devices mounted upon said vehicle, a bucket elevator between said devices, said elevator comprising an upper sprocket, a lower sprocket located when in operative position in proximity to the ground surface, and an endless carrier having substantially vertical stretches connecting said sprockets, means for moving said lower sprocket independently of said upper sprocket and relatively to said material-supplying means and away from the ground for transportation, and means for driving said elevator through said lower sprocket.

In testimony whereof, the signature of the inventor is affixed hereto in the presence of two witnesses.

CHARLES S. LINCOLN.
